UNITED STATES PATENT OFFICE

2,168,795

SIDE WALL FOR RAILWAY CARS

Garth G. Gilpin, Riverside, Ill., assignor to Standard Railway Equipment Manufacturing Company, Chicago, Ill., a corporation of Delaware

Application December 7, 1937, Serial No. 178,562

5 Claims. (Cl. 105—409)

The invention relates to railway car structure and more specifically to a side wall of an open top railway car having spaced apart upper and lower chords (or frame members) with spaced apart vertical strut-ties (or posts) connecting the chords and wall plates extending between and secured to such chords, which plates have their adjacent vertical margins formed to provide integral strut-ties, and wherein each wall plate is formed with an outwardly projecting panel (extending between the chords and the strut-ties) to increase the cubical capacity of the car. Such a wall is disclosed in Gilpin Patent No. 2,040,045 of May 5, 1936.

One of the objects of the invention is to provide a separate reinforcing element for the integral strut-tie to increase the strength thereof as a column and as a beam, which reinforcing element extends between and is also secured to upper and lower chords, and a further object is to provide a structure wherein the reinforcing element can be secured to the wall plates by the same rivets which secure the marginal portions of the wall plates together so that only one row of vertical rivets will be required, which is very desirable, as two adjacent rows of rivets, such as usually employed, materially interferes with the free discharge of the lading when the car is tipped in an unloading machine.

A further object is to so form the reinforcing element and associate it with the integral strut-tie as to not only strengthen it as a beam and column between the upper and lower chords, but to also strengthen the strut-tie against lateral deflection or buckling under load.

Such walls must be very light, as it is expensive to transport dead weight in a car and such walls must be very strong as girders to carry the load and must be very strong as vertical beams to carry the horizontal thrust of the lading, which is very great on account of the impact thereof due to the movements of the car when running.

Another object of the invention is to provide a car wall so that the component parts thereof may be secured together by bolting, riveting or welding.

Another object is to provide a car wall wherein the component parts can be made of pressed steel plates between reciprocating dies.

Another object is to provide a car which will dump the entire lading when turned upside down in an unloading machine.

In the drawings:

Fig. 1 is a fragmentary perspective view of the

exterior of the side wall of a car in accordance with my invention.

Fig. 2 is similar to Fig. 1 but shows an interior view of the car.

Figs. 3-13 show modifications hereinafter described.

In the form of my invention illustrated the wall of the car comprises spaced apart upper (2) and lower (3) chords or other frame members and a plurality of wall plates 4 extending therebetween and forming the load retaining means of the wall as well as the web plate of the wall as a girder.

Each wall plate is formed with an outwardly projecting panel 6 to increase the cubical capacity of the car. The upper (7) and lower (8) web of these panels merge into the plate adjacent the upper (2) and lower (3) chords, respectively. The side webs 9—10 of these panels merge into the plates to leave marginal portions 11—12 with the marginal portions of adjacent sheets secured together by the rivets 13.

The adjacent margins of adjacent wall sheets are formed and combined with a separate reinforcing element to provide a strut-tie between the chords 2 and 3.

The reinforcing element has a part secured to the adjacent wall plate by the same rivets which secure the wall plates together and the flange of the reinforcing element is preferably positioned between the marginal portions of the wall plates.

The reinforcing element and the flange of the wall plate are spaced apart in the plane of the overlapping portion of the wall plates and come together at their outer marginal parts and means are provided to secure these marginal parts together. (Various means are illustrated herein.) Such a construction resists the tendency of the strut-tie to deflect laterally under load either as a beam or a column.

Figs. 1 and 2 show the preferred form of the invention wherein one of the wall plates is provided with an outwardly projecting flange 20 having a reflare 21. The reinforcing element 22 is provided with a part 23 positioned between the overlapped marginal portions 11—12 of the adjacent wall plates and comprises a portion 26 spaced apart from the flange 20 and an outer portion 27 in contact with and riveted (28) to the flange 20. The reinforcing element 22 is also provided with a reflare 29 in substantially the same plane as the reflare 21. The inner portion 26 of the reinforcing element and the flange 20 converge together adjacent the upper and lower frame members respectively (at 30—31) 55

and the rivets 32 and 33 secure these converged portions together. The panel 9 of the unflanged plate merges into the plate adjacent the reinforcing element 20.

5 Fig. 3 shows a modified construction wherein the reinforcing element 35 has a straight portion 36 and the flange 37 of the wall plate is offset to provide an inner portion 38 spaced apart from the flange 35 and an outer portion in contact with and 10 secured to the flange 35 by the rivet 39.

Fig. 4 shows a construction similar to Figs. 2 and 3 but in this modification the reinforcing element 40 is provided with the offset portions 41 and 42 for the purposes set forth.

15 Fig. 5 shows a modification wherein the offset portion 50 of the reinforcing element 51 extends in a substantially straight line between the wall plate flange 11 and its place of contact with the flange 52.

20 Fig. 6 shows a construction which is functionally like Fig. 5, but comprises a reinforcing element 60 applied to the outside of the overlapping portion 61—62 of adjacent wall plates.

Fig. 7 shows a modification similar to Fig. 3 25 wherein the reinforcing element 70 is in contact with and may be secured to the web 9 of the outwardly projecting panel and wall plate; for instance, by welded material 71.

Fig. 8 shows a modification wherein the flange 30 80 and the portion 81 of the reinforcing element 82 are parallel and a tension member 83 is positioned between and secured to these elements 80 and 81, which tension member 83 has an arm 84 substantially in the plane of the panels 4 of the 35 wall plates.

Fig. 9 is similar to Fig. 8 except that the reinforcing element 90 is offset to provide portions 91 and 92.

Fig. 10 shows a modification wherein the flange 40 101 of the wall plate is provided with a reflare 102 which overlaps and is welded (103) to a reflare 104 of the reinforcing element 105.

Fig. 11 is similar to Fig. 10 except that the reinforcing element 111 engages the web 9 of the panel 45 of the wall plate and may be secured thereto by the welded material 112.

Fig. 12 shows a modification wherein the flange 120 of the wall sheet is formed with a rebent portion 121 and the reinforcing element 122 is provided with a U-shape portion 123 overlapping and secured to the rebent portion 121 by the rivet 124.

Fig. 13 shows a modification wherein the wall plate flange 130 is provided with a reflare 131 and the reinforcing element 132 is also provided with a reflare 133, said flanges 131—133 being secured together by the rivet 124. Fig. 13 shows a riveted construction and Figs. 10 and 11 show a welded construction.

60 The strut-tie is a vertical beam extending between the upper and lower chords of the side wall and a horizontal load is imposed thereon by the plastic lading in the car so that the part of the strut-tie adjacent the lading becomes the compression member of the beam and the parts of the strut-tie furthest from the lading become the tension members of the beam and it will be noted that in the several modifications disclosed herein that the area of the tension member is substantially the same as the area of the compression members so that the maximum strength of the beam is obtained from the material used.

The accompanying drawings illustrate the preferred form of the invention, though it is to be understood that the invention is not limited to

the exact details of construction shown and described, as it is obvious that various modifications thereof, within the scope of the claims, will occur to persons skilled in the art.

I claim:

5 1. In an open top railway car having spaced apart frame members, a pair of wall plates extending between and secured to said members to form a load retaining means therebetween, a portion of one of said plates overlapping a portion 10 of the other of said plates, means securing said overlapping portions together, each of said wall plates formed with an outwardly projecting panel to increase the cubical capacity of the car, one of said plates having an integral flange at a vertical margin thereof closely adjacent the overlapping portions of said plates, a reinforcing element secured to said wall plate portions by said means, said reinforcing element and said flange being spaced apart adjacent said overlapping portions the outer margin of said flange and the outer margin of said reinforcing element being substantially in contact, and means to secure said outer margins together.

2. In an open top railway car having spaced apart frame members, a pair of wall plates extending between and secured to said members to form a load retaining means therebetween, a portion of one of said plates overlapping a portion of the other of said plates, means securing said overlapping portions together, each of said wall plates formed with an outwardly projecting panel to increase the cubical capacity of the car, one of said plates having an integral flange at a vertical margin thereof closely adjacent the overlapping portions of said plates, a reinforcing element secured to said wall plate portions by said means, said reinforcing element and said flange being spaced apart adjacent said overlapping portions the outer margin of said flange and the outer margin of said reinforcing element being substantially in contact, and means to secure said outer margins together.

3. In an open top railway car having spaced apart frame members, a pair of wall plates extending between and secured to said members to form a load retaining means therebetween, a portion of one of said plates overlapping a portion of the other of said plates, means securing said overlapping portions together, each of said wall plates formed with an outwardly projecting panel to increase the cubical capacity of the car, one of said plates having an integral flange at a vertical margin thereof closely adjacent the overlapping portions of said plates, a reinforcing element secured to said wall plate portions by said means, said reinforcing element and said flange being spaced apart adjacent said overlapping portions, and a tension member secured to the outer marginal parts of said flange and said element.

4. In an open top railway car having spaced apart frame members, a pair of wall plates extending between and secured to said members to form a load retaining means therebetween, a portion of one of said plates overlapping a portion 65 of the other of said plates, means securing said overlapping portions together, each of said wall plates formed with an outwardly projecting panel to increase the cubical capacity of the car, one of said plates having an integral flange at a vertical margin thereof closely adjacent the overlapping portions of said plates, a reinforcing element secured to said wall plate portions by said means, said reinforcing element and said flange being spaced apart adjacent said overlapping portions 70, and a tension member secured to the outer marginal parts of said flange and said element.

tions between said frame members and coming together and secured together at their outer marginal parts, the spaced apart portions of said reinforcing element and said flange converging together adjacent said frame members respectively.

5. In an open top railway car having spaced apart frame members, a pair of wall plates extending between and secured to said members to form a load retaining means therebetween, a portion of one of said plates overlapping a portion of the other of said plates, means securing said overlapping portions together, each of said wall plates formed with an outwardly projecting

panel to increase the cubical capacity of the car, one of said plates having an integral flange at a vertical margin thereof closely adjacent the overlapping portions of said plates, a reinforcing element secured to said wall plate portions by said means, said reinforcing element and said flange being spaced apart adjacent said overlapping portions the outer margin of said flange and the outer margin of said reinforcing element being substantially in contact, and means to secure said outer margins together, the outer marginal parts of said reinforcing element and said flange each provided with a reflare.

GARTH G. GILPIN.
